Primary Examiner — Mitchell Siegel(74) *Attorney, Agent, or Firm* — Banner & Witcoff, Ltd.(57) **CLAIM**

The ornamental design for a golf club head, as shown and described.

DESCRIPTION

FIG. 1 is a first perspective view of a golf club head showing our new design;

FIG. 2 is a top view thereof;

FIG. 3 is a second perspective view thereof; and,
FIG. 4 is an enlarged view of FIG. 2 shown in isolation from the environment.

The broken lines immediately adjacent to the shaded area represent unclaimed boundaries of the design. The contrast in shading represents a contrast in appearance only and does not represent any particular color, material, texture or finish. The broken lines showing the remainder of the golf club are for environmental purposes only and form no part of the claimed design.
